CLAIM

The ornamental design for a shoe, as shown and described.

DESCRIPTION

FIG. 1 is a medial side view of a shoe.

FIG. 2 is a lateral side view of the shoe of FIG. 1.

FIG. 3 is a front view of the shoe of FIG. 1.

FIG. 4 is a rear view of the shoe of FIG. 1.

FIG. 5 is a top view of the shoe of FIG. 1.

FIG. 6 is a bottom view of the shoe of FIG. 1.

FIG. 7 is a front lateral perspective view of the shoe of FIG. 1; and,

FIG. 8 is a bottom perspective view of the shoe of FIG. 1. The broken lines show portions of the shoe that are unclaimed subject matter only and form no part of the claimed design.

1 Claim, 8 Drawing Sheets
